UNITED STATES PATENT OFFICE.

BOSTON CLAY, OF MUSCATINE, IOWA, ASSIGNOR TO JAMES T. SISSEL, OF MUSCATINE COUNTY, IOWA.

BUTTON-MAKING MACHINE.

1,105,757.

Specification of Letters Patent.

Patented Aug. 4, 1914.

Application filed February 11, 1914. Serial No. 818,139.

To all whom it may concern:

Be it known that I, BOSTON CLAY, a citizen of the United States, residing at Muscatine, in the county of Muscatine and State 5 of Iowa, have invented certain new and useful Improvements in Button-Making Machines, of which the following is a specification, reference being had to the accompanying drawings.

10 This invention relates to new and useful improvements in button making machines and has for its primary object the provision of such a machine so constructed that a plurality of button blanks may be simultaneously cut, so that a larger output of work with relation to the amount of labor expended will be assured.

20 A more specific object of the invention resides in the provision of such a machine which will cut a plurality of buttons independently and simultaneously if desired and deliver them in separate receptacles so that blanks formed of different materials may be cut at the same time by the machine, or so 25 that the blanks of different sizes may be cut, the machine being so constructed that all of the cutting elements may discharge into the same receptacle, or into different receptacles.

30 A further object of the invention resides in the provision of means whereby the cutting elements may be driven without interfering with the discharge of cut blanks from said elements.

35 A still further object of the invention resides in the provision of such a machine which is compact in form, which may be easily operated and which is of such structure that it may be readily manufactured or 40 assembled.

With these and other objects and advantages in view, the invention resides more particularly in the novel combination, formation and arrangement of parts more fully 45 hereinafter described and particularly pointed out in the claims hereto appended.

Reference is had to the accompanying drawings, wherein similar characters of reference designate corresponding parts 50 throughout the several views, and in which—

Figure 1 is a side elevation of the improved button blank cutting machine. Fig. 2 is a top plan view with the cover removed. Fig. 3 is a central vertical longitudinal sec-

tional view through the machine. Fig. 4 55 is a transverse central view through the machine on the line 4—4 of Fig. 3. Fig. 5 is a transverse sectional view through the machine on the line 5—5 of Fig. 3.

Referring now more particularly to the 60 accompanying drawings, the preferred embodiment of the machine is shown as including a base portion 5 at one end of which is mounted a standard 6 carrying the tail stock 7 and at the other end portion of 65 which is mounted the head 8 of the machine.

The head portion of the machine comprises a casing including inner and outer walls 9 and 10 respectively, and side walls 11. The rotary cutting elements of the machine comprise a main drive cylinder 12 and a plurality of driven cylinders 13, these cylinders being journaled in the wall 9. Each of the cylinders is provided with a longitudinal bore 14 which gradually increases in 70 diameter toward the outer end of the cylinder. Disposed in the inner end of each of the bores is a tubular saw section 15. Thus when the cylinders are rotated, each saw section is adapted to cut circular blanks and 75 these blanks are projected into the bore 14 and are moved outwardly by each successive blank which is cut and projected into the bore until they drop from the outer ends of the bore into the receiving means to be described.

It has been said that the cylinders are journaled in the inner wall 9. The main drive cylinder is journaled in a bore 16 disposed in this wall adjacent its top and central of its sides. The other rollers 13 are provided with reduced portions 17 which are journalled seated in transverse semi-circular grooves 18 formed in the top face of the wall and so positioned that the portions 95 of the rollers 13 outwardly of the wall rest upon the drive roller 12. The periphery of the drive roller and the peripheries of the driven rollers inwardly of the wall 9 are provided with geared teeth 19 whereby the 100 rollers 13 will be rotated upon rotation of the roller 12. To prevent these rollers from riding upwardly and possibly becoming displaced from their journalled grooves 18, when they are rotated, and at the same time 105 to provide a protection for the interior of the head casing, a cover 20 is pivoted to one of the side walls 11 and is provided with

depending side flanges 21, the inner of which is provided with transverse grooves 22 embracing the upper portions of the reduced section 17 of the driving cylinder 12. The 5 cover is adapted to be held in a closed position by connecting elements 23 of a latch secured to the other side wall 11 and to the free edge of the cover. For rotating the drive cylinder in such manner as not to 10 interfere with the discharge of blanks therefrom, a shaft 24 is journaled in the wall 10 in radial alinement with the cylinder. The shaft terminates short of the end of the cylinder and extending toward the cylinder 15 from the adjacent end of the shaft are a plurality of spaced bowed arms 25 which have their otherwise free ends attached to a sleeve member 26 which is threaded on that portion of the cylinder which extends 20 inwardly of the wall 9. Thus the button blanks may be projected through the cylinder and into the compartment formed by the bowed arms 25, from whence they will drop between the arms into a suitable chute member 27. The shaft 24 of the wall 10 carries a 25 belt pulley 28 whereby it may be rotated.

It is seen that the chute member 27 extends a substantial distance on each side of the arms 25. Thus in the operation of the 30 three cylinders the blanks from all of them would fall into the chute 27. To prevent this when desired, detachable chute members 29 are provided for the discharge ends of the driven cylinders 13 and these chutes 35 extend on each side of the chute 27. It will be understood that there will be considerable vibration of the machine during this operation and this vibration will materially aid in moving the blanks along the cylinder 40 bores and discharging them therefrom. It is also noted that the driven cylinders 13 may be removed by lifting the cover and then merely lifting the cylinders from their 45 positions. By this construction it is seen that cylinders adapted to cut buttons of various sizes may be substituted as desired.

The tail stock 7 is provided with a plurality of bores in which are slidably mounted integrally threaded sleeves 30 carrying at 50 their inner ends the heads 31 on which are adapted to be positioned the material from which the blanks are cut, upon advancing the retracting sleeves, the tail stock is provided with a rearward extension 32 terminating in a vertical portion 33 disposed rearwardly of the sleeves 30 and having journaled therein feed screws 34 extending into and engaging the threaded peripheries of the sleeves 30 whereby they may be advanced or retracted. It is noted that the sleeves are held against rotation by means of the projections 35 carried by the tail stock and engaging in longitudinal grooves 26 formed in the outer peripheries of the 55 sleeves. In the above description there has

been set forth the means whereby each of the cylinders may have their working material advanced independently.

From the foregoing it will be noted that an exceedingly simple machine has been provided which will cut a plurality of blanks simultaneously and which may be adapted readily for cutting blanks of different sizes. It will be understood that various minor changes and modifications within the scope of the appended claims may be made without departing in any manner from the spirit of the invention.

What is claimed is:

1. In a blank cutting machine, the combination of a support, of a saw carrying member journally carried thereby, a plurality of saw carrying members also carried by the support and having portions thereof engaging the first member, intermeshing gears formed on the engaging portions of the members, and means for rotating the first mentioned saw carrying member.

2. In a blank cutting machine, the combination with a support, of a tubular saw carrying member journaled therein, a plurality of tubular saw carrying members journally mounted on the support and engaging the first mentioned member to be rotated thereby, a cover hinged to the support and engaging the last mentioned saw carrying members to hold them in relation to the first mentioned member, and means for rotating the first mentioned member.

3. A blank cutting machine comprising a support, a tubular saw carrying member journally carried by the support, a plurality of saw carrying members also carried by the support, intermeshing gears formed on the engaging portions of the members, a drive shaft disposed in axial alinement with the first-mentioned member and terminating short of one end of said member, and means connecting the shaft and the first-mentioned member to drive said member and at the same time to permit the blanks to be discharged from the inner end of said member.

4. A button making machine comprising a support, a tubular saw carrying member journaled therein, a shaft in axial alinement with said member, a sleeve formed at the end of said shaft adjacent said member, said sleeve being threaded on the saw carrying member, and the shaft being formed with a skeleton section adjacent the sleeve whereby the blanks projected through the bore of the tubular saw carrying member will fall outwardly through the interstices thereof.

5. A blank cutting machine comprising a casing, a plurality of tubular saw members journally carried on one wall thereof, a shaft journaled in the opposite wall of the casing in axial alinement with one of said members, a plurality of spaced bowed arms

extending from said shaft toward one of said members, a sleeve formed at the terminals of said arms for engagement with the member and in alinement therewith, 5 and a chute disposed under the arms and under the discharge ends of the other tubular members.

6. A blank cutting machine comprising a vertical casing, a tubular saw carrying member journaled in the upper wall of the casing, the top edge of said wall being provided with transverse bearing grooves, tubular saw carrying members having reduced sections seated in said grooves, intermeshing 15 gears carried by all of the tubular members, means for rotating the first named member, and a cover for the casing engaging the reduced portions of the second named tubular members to hold them against displacement. 20 7. A blank cutting machine comprising a casing, a plurality of tubular saw carrying

members journally carried by one wall of the casing, a shaft journaled in the opposite wall of the casing in axial alinement with one of the said members, a plurality of 25 spaced bowed arms extending from the adjacent end of the shaft, a sleeve carried by said arms and engaging the member in alinement therewith to rotate the same, a chute disposed under the arms and also disposed 30 under the discharge ends of the other tubular members, and a plurality of detachable chute members adapted to be secured to said other tubular members and to extend at the sides of the first mentioned chute member. 35

In testimony whereof I hereunto affix my signature in the presence of two witnesses.
